UNITED STATES PATENT OFFICE.

HUBERT EVERIST, OF SIOUX CITY, IOWA.

MACHINE FOR DISTRIBUTING CONCRETE.

Application filed March 17, 1927. Serial No. 176,141.

The invention relates to a machine for distributing concrete.

The object of the present invention is to improve the construction of machines for distributing concrete, and more especially the bucket driving and tripping mechanism for causing the bucket to traverse the boom and for tripping the bucket to discharge its contents and to provide simple, practical and efficient bucket actuating and tripping mechanism of strong, durable and comparatively inexpensive construction adapted to effect a tripping of the bucket and a discharging of the contents automatically through the means for actuating the bucket to move the same along the boom.

A further object of the invention is to provide bucket actuating and tripping mechanism adapted to effect a positive tripping of the bucket and a releasing of the bottom door thereof so that the concrete will be discharged over the surface or subgrade at the desired point.

Another object of the invention is to provide mechanism of this character in which the tripping mechanism will be relieved of strain during both the outward and inward movements of the bucket in traversing the boom so that there will be no liability of accidentally releasing the door of the bucket during the outward movement or subjecting tripping mechanism to undue strain during either movement.

A further object of the invention is to provide automatically operated means for locking the door in its closed position adapted to be actuated by a cam or similar device but capable when moved to its locked position of securely maintaining the door of the bucket in such position while the bucket is being charged.

A further object of the invention is to arrange the mountings of the door of the bucket so that the door in its opening movement will not project materially below the lower extremity of the bucket and not be liable to come in contact with any obstruction which the bucket will clear.

Furthermore it is the object of the invention to provide bucket actuating mechanism having a drive shaft adapted to be continuously operated in one direction for moving the bucket in either direction in traversing the boom.

With these and other objects in view, the invention consists in the construction and

novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:—

Figure 1 is a side elevation of a portion of a concrete distributing machine provided with bucket actuating and tripping mechanism constructed in accordance with this invention.

Fig. 2 is an end elevation partly in section illustrating the arrangement of the drums and the shifting mechanism for controlling the cables which actuate the bucket.

Fig. 3 is an enlarged transverse sectional view the bucket being shown in elevation.

Fig. 4 is a detail longitudinal sectional view through the boom and carriage illustrating the construction of the bucket tripping mechanism and showing the position of the same when the bucket is closed and locked.

Fig. 5 is a similar view illustrating the arrangement of the tripping mechanism when the door of the bucket is open and the bucket is traveling inwardly along the boom.

Fig. 6 is an enlarged plan view of the bucket actuating mechanism.

Fig. 7 is a plan view of the carriage and tripping mechanism.

Fig. 8 is an enlarged side elevation of the lower portion of the bucket illustrating the manner of mounting and actuating the hinged bottom door.

Fig. 9 is a transverse sectional view on the line 9—9 of Fig. 6 illustrating the arrangement of the clutches and the sections of the drum.

In the accompanying drawings in which is illustrated the preferred embodiment of the invention 1 designates a boom composed of spaced channels 2 suitable connected together and forming exterior grooves or ways at opposite sides of the boom for the reception of rollers 3 of a carriage 4 of a bucket 5. The boom 1 is shown in the accompanying drawings as pivoted by a vertical pivot 6 to a supporting structure 7 so as to swing horizontally but the boom may be mounted in any desired manner to swing both vertically

and horizontally if desired. The channels 2 are spaced apart to provide an intervening space 8 for the reception of a pair of inner sheaves 9 and 10 and an outer sheave 11 around which are trained cables 12 and 13. The cables 12 and 13 extend upwardly from the inner sheaves 9 and 10 to a drum composed of drum sections 14 and 15 which are mounted on a drive shaft 16 and which are adapted to be connected with the same by suitable clutches 17 and 18. The clutches 17 and 18 are composed of separable sections connected respectively with the shaft and with the drum sections 14 and 15. The inner sections of the clutches are connected with the drum sections and the outer sections are slidably mounted on the drive shaft and are suitably interlocked with the same whereby they are caused to rotate therewith and when either of the outer sections of the clutches 17 and 18 is engaged with its coacting inner section the drum section carrying such coacting inner clutch section will be rotated with the shaft. The slideable sections of the clutches 17 and 18 are connected with a suitable shifting lever 19 fulcrumed intermediate of its ends at 20 to a suitable bracket 21 and having an approximately inverted U-shaped upper portion 22 which is connected with the slideable clutch sections by suitable collars 23. The collars 23 are mounted in annular grooves 24 of the outer clutch sections which rotate freely while the collars are held against rotation by their connection with the shifting lever. The shifting lever is provided at its terminal portion 25 with a fork to receive the adjustable collar. The fork 25 is located at one side of the U-shaped portion 22 which is provided at its opposite side with an enlarged portion 26 having an opening receiving the other collar. By shifting the lever one of the slideable clutch sections may be moved into engagement with the clutch section of the adjacent drum section and the other slideable collar will be carried out of engagement with its cooperating clutch section and the shifting lever may also be arranged in a neutral position as illustrated in Fig. 2 of the drawings with both of the slideable clutch sections in a disengaged position. The U-shaped portion 22 arches the drum sections 14 and 15 which are provided at their outer sides with flanges. The inner ends of the drum sections engage a friction disk 27 which is interposed between the drum sections. The disk 27 operates as a friction disk, and two coiled springs 27^a are interposed between the outer ends of the drum sections 14 and 15 and collars 27^b fixed to the shaft 16. The springs exert a thrust on each drum section toward the friction disk 17 to prevent continued rotation of the drum sections when the loose cable is paid out. The springs 27^a and the collars 27^b are located within the clutch sections 18, which are tubular and constitute hub extensions of the drums, but any other form of clutch mechanism may be employed. The drive shaft 16, which is provided at one end with a beveled gear 28 is designed to rotate continuously in one direction indicated by the arrow in Fig. 1 of the drawings and either of the drum sections may be connected with the drive shaft for winding on it the cable connected to it. The cable 12 passes beneath the inner sheave 9 and extends outwardly beneath the boom to the outer sheave 11 and it passes upwardly at the outer side thereof to the top of the said outer sheave and then extends to the carriage 4 and is connected therewith by the means hereinafter described whereby when the cable 12 is wound around the drum section 14, the carriage 4 and the bucket 5 will be moved outwardly on the boom. The other cable 13 extends from the inner sheave 10 to the carriage 4 and is connected with the same by the means hereinafter described, whereby when the cable 13 is wound around the drum section 15 the carriage 4 and the bucket 5 will be moved inwardly along the boom. When one of the drum sections is clutched to the drive shaft for winding its cable thereon the other drum section is loose and slips on the shaft and permits the cable to be unwound from it by the pull of the carriage and the bucket on such cable. The shifting of the clutch operating lever will reverse the direction of the bucket and when it is desired to stop the travel of the bucket the shifting lever is moved to its neutral position. The sheaves are grooved as shown and the cables 12 and 13 are connected with the carriage by means of a trip lever 29 operating in a slot 30 in the top of the carriage and carrying a connecting link 31 pivoted at 32 to the trip lever and extending in advance and in rear of the same and provided at its ends with suitable eyes or openings 33 for the attachment of the adjacent terminal portions of the cables 12 and 13. The slot 30 permits the limited movement of the trip lever and its end walls form stops for limiting the movement of the trip lever independently of the carriage and when the carriage is moving outwardly the trip lever lies against the front wall of the slot 30 and relieves the tripping mechanism of undue strain when the carriage is moving inwardly along the boom the trip lever 29 occupies a position adjacent and in contact with the inner end wall of the slot 30 and is supported by the inner end wall during such movement until it is actuated by the locking mechanism of the door 34 of the bucket as hereinafter fully explained. The tripping lever is provided with a circular head 35 constituting a central sleeve and arranged on a rock shaft 36 between side sleeves or collars 37 fixed to the shaft 36 by

means of suitable fastening devices 38. Any suitable means may be employed for rigidly securing the side sleeves to the rock shaft and the said side sleeves are provided with 5 segmental recesses 39 extending partially around the circumference of the side sleeves and leaving solid sections 40 and receiving laterally projecting lugs 41 consisting of solid sections of the central sleeve or head 35 and formed by recessing the latter at opposite sides thereof. The central sleeve is provided at opposite sides with segmental recesses 42 in which the solid sections 40 of the side sleeves operate. The above construction 10 constitutes substantially a clutch which, it will be seen, is mounted on the carriage and travels with the bucket along the boom. The rotary movement of the trip lever on the rock shaft is limited by the end walls of 15 the slot 30 and the pivotal connection 32 between the link 31 and the trip lever 29 permits the pivotal movement of the trip lever without altering the longitudinal position of the link 31 with relation to the attached 20 portions of the cables. The segmental recesses of the side sleeves permit an independent movement of the rock shaft which is provided at its ends with crank arms 43 connected at their outer ends by suitable 25 pivots 44 with the upper ends of long upper links 45 pivoted at 46 to upper ends of short lower links 47 which are pivotally connected at their lower ends to the door 34 by a suitable pivot 48. The upper and 30 lower links are connected at their adjacent jointed ends by the pivot 46 with an oscillatory link 49 which causes the pivot 46 to travel through an arc whereby the upper and lower links are maintained in proper 35 position with relation to the hinged door for constantly exerting a pull in the proper direction to close the same and the said link 49 enables the hinged door 34 to be fully closed and to swing properly to its open position.

The bucket which has a tapered lower portion is provided at one side of its lower extremity with an outlet arranged at an 40 inclination and the hinged door is inclined when closed as clearly illustrated in Fig. 1 of the drawings. The hinged door which may be mounted in any desired manner is preferably provided with movable hinge elements 50 extending across the terminal portions of the door 34 and arranged at an 45 inclination when the door is closed and provided at their upper ends with upwardly projecting eyes 51 which are pivoted to similar eyes 52 of fixed hinge elements or brackets 53 to which the links 49 are connected by suitable pivots 54. The eyes of the fixed and movable hinge elements are connected by suitable pintles 55 and the pivoted point of the door is arranged a sufficient distance above the discharge opening to cause 50 the hinged door in swinging to an open position to move upwardly so that the lower edge of the door will not extend materially below the lower edge of the bucket and will not strike obstructions which the bucket will 55 clear. The rock shaft is journaled in suitable bearings 56 which are mounted upon shoulders 57 of the carriage. The shoulders have horizontal top portions and the bearings are arranged at the outer ends of the 60 top portions. The rock shaft is equipped at the inner side of the bearings with cam actuated arms 58 which are arranged in a horizontal position in contact with the shoulders as clearly illustrated in Fig. 1 of 65 the drawing when the door of the bucket is closed. The cam actuated arms are arranged at slightly less than a right angle to the crank arms and when the cam actuated arms are swung downwardly and forwardly 70 to the horizontal position shown in Fig. 1 of the drawing the upper ends of the crank arms are carried slightly beyond the dead center to form a lock for holding the door 75 closed. As the pivots 44 are carried forwardly beyond the central vertical plane of the transverse rock shaft any pressure on the hinged door will tend to swing the arms 43 forwardly and as the 80 forward movement of the said arms 43 is limited by the contact of the cam actuated arms 58 the door will be firmly locked and held in such closed position until tripped and released by the operation of the tripping 85 lever or cable as hereinafter fully explained. As clearly shown in Fig. 1 of the drawing the cams 59 which are located at opposite sides of the boom consist of laterally projecting flanges of an approximately inverted U-shaped member 60 which saddles the boom 90 as clearly shown in Fig. 3 of the drawings. The flanges which form the cams 59 have inclined upper and lower portions and a rearwardly extending approximately horizontal portion 61 and are arranged in the path of 95 the arms 58 which assume an upright position when the locking mechanism is tripped and the door 34 is released and permitted to move to its open position. When the bucket moves inwardly the upwardly extending arms 58 100 which are provided at their outer ends with rollers 62 are carried into engagement with the cams and the rollers engage the underfaces of the flanges forming the cams 59 and the arms 58 are gradually swung downwardly to a horizontal position and the 105 crank arms are moved upwardly and carried forwardly beyond the dead center to lock the door in its closed position. The upward movement of the crank arms closes the door and the door remains locked until the bucket receives its charge and is carried outwardly 110 to its discharging position. When the bucket moves outwardly the rollers will pass beneath the flanges and the door will con-

tinue in its locked position until the bucket reaches the portion of the surface or sub-grade to be coated with the concrete. When the bucket has been carried outwardly by the 5 cable 12 to the desired position the drum section 14 is unclutched from the drive shaft and the drum section 15 is clutched to the same to pull upon the cable 13 which will first operate to swing the trip lever from the 10 position shown in Fig. 4 of the drawing to that illustrated in Fig. 5. When the trip lever is moved rearwardly or backwardly by the cable 13 its lugs will engage the adjacent shoulders formed by the solid portions 40 15 of the side sleeves 39 and the rock shaft will be rotated in a rearward direction thereby carrying the pivot 44 to the rear of the dead center which releases the hinged door and permits the same to swing to its open position. 20 This rearward movement of the trip lever is limited by the rear wall of the slot 30 of the carriage and the carriage may be moved inwardly or backwardly at the desired speed to distribute its contents as 25 required. The segmental recesses of the side sleeves are of sufficient size to permit the rock shaft to rotate freely independently of the trip lever a sufficient distance to permit the hinged door 30 to move to its open position 30 for discharging the contents of the bucket. When the bucket is carried inwardly by the cable 13 to return the bucket to its charging position the rollers 62 and the arms 58 will be gradually swung down- 35 wardly in a forward direction to the position shown in Fig. 1 and this movement of the rock shaft will carry the shoulders of the side sleeves into engagement with the lugs of the tripping lever and the latter will be 40 rotated in a forward direction and carried into engagement with the front wall of the slot 30 by the forward rotation of the rock shaft incident to the action of the cams. The horizontal portions 61 of the flanges 45 which form the cams 59 are arranged to maintain the hinged door 34 in its closed position by confining the arms 58 in the horizontal position shown in Fig. 1 while the bucket is in charging position and until 50 there is a pull on the cable 12 which will prevent the tripping arm from moving rearwardly in the slot 30 and operating the rock shaft to trip the locking mechanism for releasing the hinged door. There will be no 55 liability of the hinged door being accidentally released and permitted to open during the outward movement of the bucket as the weight of the contents of the bucket will 60 positively prevent any liability of the arms 58 swinging upwardly from their horizontal position. The arms 58 will remain in such horizontal position until the rock shaft is positively rotated by reverse pull on the tripping lever.

65 The carriage which may be of any desired

construction is composed of spaced sides 63 and a connecting transverse member 64. The sides have upper vertical portions and lower downwardly diverging portions. The shoulders 57 are formed by approximately inverted L-shaped brackets or members consisting of vertical outer portions and inwardly extending upper horizontal portions which are secured to the sides of a bucket adjacent the angle formed by the vertical and inclined portions of the sides. The horizontal cross member is located intermediate of the ends of the vertical portions of the sides of the carriage and the said sides extend upwardly at opposite sides of the channels 2. The rollers 3 which are provided with outer peripheral flanges extend into the grooves or ways of the channels and run upon the lower flanges of the channels as clearly illustrated in Fig. 3 of the drawings. The rollers are preferably arranged in pairs as clearly shown in Fig. 7 and are mounted upon suitable stub axles 65.

85 While the machine is designed primarily for distributing concrete any other material 90 may be handled as will be readily understood.

Also one of the salient features of the invention is that all tripping, traveling and dumping mechanism is arranged so that the 95 concrete or other materials do not come in contact with the movable parts.

What I claim is:

1. In a machine of the class described, 100 the combination of a bucket provided with an outlet and having a hinged door and locking mechanism for retaining the door in its closed position comprising a rock shaft having a crank arm and a cam actuated arm disposed at an angle, the crank arm being 105 arranged to be carried to one side of the dead center in the closing movement of the door, means for limiting the movement of the cam actuated arm, a relatively long upper link pivoted to and depending from the crank 110 arm, a relatively short lower link pivoted to the lower end of the long link and to the door, and an oscillatory link pivoted to the bucket and connected with the said links at the adjacent ends thereof for causing the 115 said ends of the links to move in an arc in the proper direction for maintaining a constant pull on the door in the closing movement thereof whereby the weight of the door will retain the mechanism in its locked 120 position.

2. In a machine of the class described, the combination of a boom, a bucket having a carriage movable along the boom, said bucket being also provided with an outlet and having a hinged door, a rock shaft mounted on the carriage and having a cam actuated arm, and a crank arm connected with the hinged door and arranged to be 125 carried beyond the dead center for locking 130

- the door in closed position, a tripping mechanism comprising a tripping lever pivotally mounted on the rock shaft and adapted to be connected with a means for moving the bucket inwardly and outwardly and having a limited movement, and a clutch mounted on the rock shaft and cooperating with the tripping lever whereby the rock shaft may be rotated by the tripping lever to release the door. 75
3. In a machine of the class described, the combination of a boom, a bucket having a carriage movable along the boom, said bucket being also provided with an outlet and having a hinged door, a rock shaft mounted on the carriage and having a cam actuated arm, and a crank arm connected with the hinged door and arranged to be carried beyond the dead center for locking the door in closed position, a tripping mechanism comprising a tripping lever pivotally mounted on the rock shaft and adapted to be connected with a means for moving the bucket inwardly and outwardly and having a limited movement, a sleeve fixed to the rock shaft, said sleeve and tripping lever having cooperating means whereby the tripping lever is adapted to rotate the rock shaft for releasing the door 90 when there is an inward pull on the tripping lever. 95
4. In a machine of the class described, the combination of a boom, a bucket movable along the boom and having an outlet and provided with a hinged door, locking mechanism for holding the door in its closed position comprising a rock shaft having a cam actuated arm, and a crank arm connected with the hinged door and adapted to be carried to a position beyond the dead center for holding the door in closed position, tripping mechanism comprising a tripping lever mounted on the rock shaft and designed to be connected with the means for moving the bucket inwardly and outwardly, a clutch fixed to the rock shaft adjacent the lever, said clutch and lever having cooperating means for causing rotation of the rock shaft to release the door when the tripping arm is moved inwardly, and spaced means located at opposite sides of the tripping lever for limiting the pivotal movement thereof. 100
5. In a machine of the class described, the combination of a boom, a bucket movable along the boom and having an outlet and provided with a hinged door, locking mechanism for holding the door in its closed position comprising a rock shaft having a cam actuated arm, and a crank arm connected with the hinged door and adapted to be carried to a position beyond the dead center for holding the door in closed position, tripping mechanism comprising a tripping lever mounted on the rock shaft and de- 115
- signed to be connected with the means for moving the bucket inwardly and outwardly, a member fixed to the rock shaft adjacent the lever, said member and lever having cooperating means for causing rotation of the rock shaft to release the door when the tripping arm is moved inwardly, said tripping lever operating in a slot having opposite walls forming stops for limiting the movement of the tripping lever. 120
6. In a machine of the class described, the combination of a boom, a bucket movable along the boom and having an outlet and provided with a hinged door, locking mechanism for holding the door in its closed position comprising a rock shaft having a cam actuated arm, and a crank arm connected with the hinged door and adapted to be carried to a position beyond the dead center for holding the door in closed position, a tripping mechanism comprising a tripping lever mounted on the rock shaft and de- 125
- signed to be connected with the means for moving the bucket inwardly and outwardly and provided with a head having segmental recesses forming laterally projecting lugs and sleeves fixed to the shaft at opposite sides of the tripping lever and having segmental recesses receiving the said lugs and forming solid portions cooperating with the said lugs for rotating the rock shaft and for also oscillating the tripping lever to carry the same to the forward limit of its swing when the locking mechanism is operated to close and lock the door. 130
7. In a machine of the class described, the combination of a boom, a bucket having a hinged door at the bottom, a carriage movable along the boom and secured to the bucket and provided at opposite sides with shoulders formed by approximately inverted L-shaped members, a rock shaft extending across the carriage and journaled on the said shoulders and provided with crank arms and with cam actuated arms, the cam actuated arms being arranged to engage the shoulders for limiting the movement of the rock shaft when the crank arms are carried to a position beyond the dead center, means for connecting the crank arms with the hinged door, and a cam located in the path of the crank arms. 135
8. In a machine of the class described, the combination of a boom, a bucket having a hinged door at the bottom, a carriage movable along the boom and secured to the bucket and provided at opposite sides with shoulders formed by approximately inverted L-shaped members, a rock shaft extending across the carriage and journaled on the said shoulders and provided with crank arms and with cam actuated arms, the cam actuated arms being arranged to engage the shoulders for limiting the movement of the rock shaft when the crank arms are carried to a posi- 140

tion beyond the dead center, means for connecting the crank arms with the hinged door, and a cam consisting of an approximately inverted U-shaped member saddling the boom and provided at opposite sides thereof with laterally projecting flanges located in the path of the cam actuated arms and having inclined portions and a rear approximately horizontal portion, said cams being adapted to actuate the rock shaft to close the hinged door, lock the same and maintain the same in locked position while the bucket is in charging position.

9. In a machine of the class described, the combination of a boom, a bucket movable along the boom, means for supporting the bucket, a clutch carried by said supporting means and movable along the boom with the bucket, said bucket being also provided with an outlet having a movable door, locking mechanism for holding the door in its closed position comprising a rock shaft and means controlled by the rock shaft for holding the door in its closed position, and a tripping lever, said tripping lever and rock shaft being provided with cooperating means whereby the tripping lever is adapted to rotate the rock shaft for releasing the door.

10. In a machine of the class described, the combination of a boom, a bucket movable along the boom, means for supporting the bucket, a clutch carried by said supporting means and movable along the boom with the bucket, said bucket being also provided with an outlet having a movable door, locking mechanism for holding the door in its closed position comprising a rock shaft and means controlled by the rock shaft for holding the door in its closed position, a tripping lever mounted on the rock shaft, and a member fixed to the rock shaft adjacent to the lever, said member and lever having cooperating means for causing a rotation of the rock shaft to release the door.

11. In a machine of the class described, the combination of a boom, a bucket movable along the boom, means for supporting the bucket, a clutch carried by said supporting means and movable along the boom with the bucket, said bucket being also provided with an outlet having a movable door, locking mechanism for holding the door in its closed position comprising a rock shaft and means

controlled by the rock shaft for holding the door in its closed position, a tripping lever 55 mounted on the rock shaft, and a sleeve fixed to the rock shaft and having a segmental recess receiving the same, said sleeve being arranged to be engaged by the tripping lever for rotating the rock shaft to release the 60 door.

12. In a machine of the class described, the combination of a boom, a bucket movable along the boom, means for supporting the bucket, a clutch carried by said supporting 65 means and movable along the boom with the bucket, said bucket being also provided with an outlet having a movable door, locking mechanism for holding the door in its closed position comprising a rock shaft and means 70 controlled by the rock shaft for holding the door in its closed position, tripping mechanism comprising a tripping lever mounted on the rock shaft and provided at opposite sides with laterally projecting lugs, and 75 sleeves fixed to the rock shaft and having a segmental recess fixed to the lugs and having solid portions cooperating with the lugs whereby the tripping lever is adapted to rotate the rock shaft to release the door. 80

13. In a machine of the class described, the combination of a boom, a bucket movable along the boom and having an outlet provided with a hinged door, locking mechanism for holding the door in its closed position comprising a rock shaft having a cam actuated arm, and a crank arm connected with the hinged door and adapted to be carried beyond dead center for locking the door closed, tripping mechanism comprising a 90 tripping lever on the rock shaft cooperating with means for kicking the crank arm over dead center to release the door when pulled in one direction, the said lever working in a slot having opposite walls forming stops for 95 limiting movement of the tripping lever, a cam cooperating with the cam actuated arm to rotate the rock shaft, said cam being placed on the boom so as to cause the tripping lever to engage the forward wall of the 100 slot just prior to the bucket reaching loading position, and maintaining such position until the bucket starts its rearward travel.

In testimony whereof I have hereunto set my hand.

HUBERT EVERIST.
